UNITED STATES PATENT OFFICE.

WILLIAM SCOTT, OF MEDFORD, MASSACHUSETTS.

SIPHON WATER-CLOSET.

SPECIFICATION forming part of Letters Patent No. 415,128, dated November 12, 1889.

Application filed November 22, 1888. Serial No. 291,604. (No model.)

To all whom it may concern:

Be it known that I, WILLIAM SCOTT, of the town of Medford, in the county of Middlesex and State of Massachusetts, have invented 5 certain new and useful Improvements in Siphon Water-Closets, of which the following is a full, clear, and exact description.

The improvement of this invention consists, in substance, in the combination, with a water-closet bowl having, preferably, a flushing-rim, or otherwise suitably adapted to be flushed, and two water-traps with a column of air between and located in the discharge-passage of the bowl and making a siphon, a single water-supply pipe leading from a tank or other suitable supply, and an opening and closing valve to open and close said water-pipe, of two separate water ways or passages leading from and both always in open communication with said water-pipe and one in communication with the flushing means of the bowl and the other, of less area than said water-pipe, directly with the air-column between the water-traps, whereby with said 25 valve opened the water from the water-pipe is delivered simultaneously through one of said water-ways to the flushing means and through the other of said water-ways to the air-column between the water-traps and with 30 said valve closed substantially only to the flushing means.

In the drawing forming part of this specification the figure is a central vertical section of the contrivances of this invention, some 35 parts, however, being shown in elevation.

In the drawing, A is a water-closet bowl, which has a flushing-rim B, a water-trap C, a discharge-passage D, leading from said trap C, a water-trap E in said passage D, a column 40 F of air between said traps C E, a waste-pipe G (shown as broken off) in continuation of the discharge-passage D of the bowl, a water-supply pipe H, and a water-tank J, to which said pipe H is connected and of which it constitutes the discharge, and has an opening and closing valve K, for opening and closing it, all substantially as well known, except as to the features of this invention hereinafter particularly described. The discharge-passage 45 D of the bowl is the longer leg of a siphon, of which the water-trap C at the bowl

is the shorter leg. The discharge-pipe H of the tank connects with a water-way L, which leads and opens to the flushing-rim B of the bowl, and also with a water way or passage 55 M, preferably of less area than the pipe H, that leads and opens to the longer leg of the siphon-discharge D, and it is shown opening to said discharge D at the upper end of the column F of air between the traps C E. The 60 walls a of this water-way M, as plainly shown, project beyond the wall L of and into and across the water-way L, which leads to the flushing-rim, and thus, as will hereinafter appear, the water-way M is guarded and protected against the entrance of water from the supply-pipe H, common to it and the water-way L of the flushing-rim.

Under the arrangement of the water-ways L M of the bowl, and in communication with 70 each other and with a water-supply pipe, all as has been described, first, with the valve K opened, water is then delivered to both of said water-ways simultaneously, and in part entered through the flushing-rim into the 75 bowl and in part into the longer leg of the siphon-discharge, in the first instance flushing the bowl and in the second instance starting siphonic action of the discharge-passage, and thus securing the discharge of the 80 contents of the bowl, and, second, with the valve K closed the water which then flows through the water-supply H being, as well known, of a greatly-reduced volume or body as compared with its volume when the valve 85 is opened, is substantially all entered into the water-way L and delivered to the flushing-rim to refill the bowl-trap C, the siphonic action of the discharge during the meantime having stopped because of the admission of air to 90 said discharge, for the reason that at all parts of its flow its quantity or volume is not sufficient to fill the water-way L to an extent such that any will or can enter into the water-way M leading to the siphon-discharge. 95

In order that this afterflow of water to the bowl to refill its trap may be always sufficient for the purpose, it is preferable to provide a supply of water supplemental, as it were, to the main supply of water, with the valve 100 opened, and a well-known method or means for this purpose is to provide the tank with a

water-chamber J² at its bottom, in communication by ports b with the discharge-pipe H of the tank, so that when the valve is opened water may be accumulated therein for being, 5 when the valve is closed, afterward delivered to the discharge-pipe H and thence conducted to the bowl, as stated. However, this constitutes no part of this invention, and, again, in lieu thereof, any other of the well-known ways 10 of supplying a limited quantity of water to the water-supply pipe to be conducted to the bowl after the valve of such pipe is closed may be used.

The water-way M, leading to the siphon-discharge D, preferably, should also serve as a passage for air to pass into said discharge to break its siphonic action, and, as shown, the water-way is so adapted to act.

The bowl for being flushed may be otherwise adapted, as well known, than by the way or means—such as a flushing-rim B—herein particularly described—as, for instance, by providing the bowl with a fan or spreader located at and over the water-inlet of the 25 bowl.

The discharge-passage D of an earthenware water-closet bowl has a flange N, which is integral with it and which makes one part of the connection for bowl with the metal waste-pipe 30 G in continuation of the discharge D.

O is a metal flange or ring surrounding and suitably attached, as well known, to the waste-pipe G and opposite to the under face of the bowl-flange N, and between the two 35 flanges is a packing P, of putty or other such like material. The waste-pipe G is entered into the discharge-passage D, which is of larger diameter than the external diameter of the pipe, so as to leave an annular space Q 40 between the two and about the waste-pipe. This space Q at its upper end is open to the water-way of the passage D and at its lower end it is closed by the packing P between the flanges N O.

45 The space Q between the waste-pipe G and discharge-passage D of the bowl and within the latter forms a receptacle for the deposit and constant retention of water, whereby the packed joint between the flanges of the 50 waste-pipe and bowl is water-sealed and the escape of obnoxious gases theretofore thus prevented.

The connection of waste-pipe G with the discharge-passage D of bowl and of the flange 55 N of bowl and metal flange O, all as described, constitute no part of this invention, but form the subject-matter of separate application for Letters Patent of the United States, Serial No. 308,183.

Having thus described my invention, what 60 I claim, and desire to secure by Letters Patent of the United States, is—

1. The combination, with a water-closet bowl adapted to be flushed and having two water-traps with a column of air between located in the discharge-passage of the bowl and making a siphon, a single water-supply pipe leading to the flushing means of the bowl, and an opening and closing valve to open and close said water-pipe, of two separate 70 water ways or passages leading from and both always in open communication with said water-pipe, and one in communication with the flushing means of the bowl and the other directly with the air-column between the 75 water-traps and of an area less than the area of the water-pipe, whereby with said valve opened the water from the water-pipe is delivered simultaneously through one of said water-ways to the flushing means and through 80 the other of said water-ways to the air-column between the water-traps, and with said valve closed substantially only to the flushing means, substantially as and for the purposes described. 85

2. The combination, with a water-closet bowl adapted to be flushed and having two water-traps with a column of air between located in the discharge-passage of the bowl and making a siphon, a single water-supply 90 pipe leading to the flushing means of the bowl, and an opening and closing valve to open and close said water-pipe, of two separate water ways or passages L M, leading from and both always in open communication with said water-pipe, and one L in communication with the flushing means of the bowl and the other M directly with the air-column between the 95 water-traps, and having a projection of its walls a into and across the water-way L, 100 whereby with said valve opened the water from the water-pipe is delivered simultaneously through one L of said water-ways to the flushing means, and through the other M of 105 said water-ways to the air-column between the water-traps, and with said valve closed substantially to the flushing means, substantially as described, and for the purposes specified.

In testimony whereof I have hereunto set my 110 hand in the presence of two subscribing witnesses.

WILLIAM SCOTT.
